UNITED STATES PATENT OFFICE.

JOSIAH CLEMENT CHANDLER, OF LONDON, ENGLAND.

WASHER OR SCRUBBER FOR GAS.

SPECIFICATION forming part of Letters Patent No. 486,927, dated November 29, 1892.

Application filed September 12, 1891. Serial No. 405,531. (No model.)

To all whom it may concern:

Be it known that I, JOSIAH CLEMENT CHANDLER, a subject of the Queen of Great Britain, residing at Brixton, England, have invented 5 new and useful Improvements in Washers or Scrubbers for Gas, of which the following is a specification.

My invention relates to apparatus for washing or scrubbing gas, and especially to apparatus of the kind described in the specification of Letters Patent No. 406,124, dated July 2, 1889, in which the wetted surface against which the gas impinges is composed of bundles of laths.

15 According to my invention, instead of employing laths, I make use of boards having therein a number of saw cuts or slits for affording a large amount of wetted surface. In practice a number of such boards are advantageously made up into a bundle, suitable distance-pieces being placed between them.

To enable my invention to be fully understood, I will describe the same with reference to the accompanying drawings, in which—

25 Figures 1 and 2 are side and end views, respectively, of a bundle of my boards adapted for use in gas washing or scrubbing apparatus of the kind in which the gas passes horizontally through the same—as, for instance, in 30 the apparatus described in the specification of Letters Patent No. 199,450, dated January 22, 1878. Fig. 3 is a sectional elevation showing how the said bundle may be held in position in the washing apparatus; and Fig. 4 is a section on the line $\alpha\alpha$, Fig. 3. Figs. 5 and 6 are views similar to Figs. 1 and 2, respectively, showing the arrangement of the boards when the gas is caused to pass through them from the center toward the periphery—for instance, 40 as described in the specification of Letters Patent No. 206,736, dated August 6, 1878. Figs. 7 and 8 are a sectional elevation and a longitudinal section showing how the bundles in this case may be held in position.

45 Similar letters of reference indicate corresponding parts in the several figures.

$a a$ indicate the boards; $b b$, the slits or saw cuts therein, leaving a series of fingers b' ; $c c$, the distance-pieces between the boards, and

50 $d d$ bolts passing through the boards and through the distance-pieces and serving to clamp the whole together.

In practice I advantageously arrange a series of segmentally-shaped bundles, such as are shown in Figs. 1 and 5, to form disks, 55 which are caused to revolve in order to retain the surfaces properly wetted in the usual well-known manner. When the gas is to pass through the bundles in a horizontal direction, the boards are arranged as shown in Figs. 1 60 and 2—that is to say, side by side—so that the gas will pass through the various slits in the boards.

As shown in Figs. 3 and 4, several bundles are clamped between pairs of arms $e e$ to form 55 a disk, the said arms being secured at their inner ends to a hub or boss f and at their outer ends connected by plates $g g$. $h h$ are cross-bars bolted between the plates $g g$ on opposite sides of the bundles in order to retain 70 the said bundles in their proper positions between the arms.

In the arrangement shown in Figs. 5 and 6, which is adapted for use when the gas passes radially through the bundles forming the disk, 75 the said bundles are advantageously carried between two metal plates $i i$ and held in place by cross-bars $j j$ and bolts k , as shown in Figs. 7 and 8.

Having now particularly described and ascertained the nature of my said invention and in what manner the same is to be performed, I declare that what I claim is—

1. A revoluble washer or scrubber for gas, consisting of a series of boards, each made of 85 a single piece of wood having a series of fingers b' , extending in opposite directions from the center or body of the wood, as shown and described.

2. A revoluble washer or scrubber for gas, 90 consisting of a series of bundles of boards arranged around a common center, as set forth, each board being made of a single piece of wood having a solid center and a series of fingers b' , extending from the opposite edges to 95 such solid portion.

JOSIAH CLEMENT CHANDLER.

Witnesses:

G. F. REDFERN,

JOHN E. BOUSFIELD,

Of the firm of G. F. Redfern & Co., 4 South Street, Finsbury, London, Patent Agents.
